UNITED STATES PATENT OFFICE.

CHARLES FAERBER AND JOHN HAMPTON SMITH, OF ALEXANDRIA, LOUISIANA.

GARBAGE-CAN.

1,207,006.

Specification of Letters Patent.

Patented Dec. 5, 1916.

Application filed October 21, 1915. Serial No. 57,153.

To all whom it may concern:

Be it known that we, CHARLES FAERBER and JOHN HAMPTON SMITH, citizens of the United States, residing at Alexandria, in 5 the parish of Rapides and State of Louisiana, have invented certain new and useful Improvements in Garbage-Cans; and we do declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to garbage cans and the like and has for its object to provide a receptacle for garbage, ashes and other refuse which is so constructed and arranged that 20 the top or cover of the can and the handle for transporting the can are connected in such way that the contents of the can can be conveniently and expeditiously emptied, while at the same time the top or cover of 25 the can can be maintained in proper effective position on the can without danger of accidental displacement or removal.

A further object of the invention is to 30 provide a can or receptacle and a top or cover, and a handle so arranged that when the cover and handle are swung into position for emptying the contents of the can or receptacle that the said cover and handle will be maintained in its proper position, so 35 that it can be quickly and readily moved into its normal position for covering the can or receptacle.

With these and other objects in view the 40 invention consists in the novel construction and arrangement of the parts, and particularly in the arrangement of the cover and handle and its pivoted connection with the body of the can.

Referring to the accompanying drawing— 45 Figure 1 is an elevation of the can or receptacle constructed in accordance with this invention. Fig. 2 is an elevation illustrating the can or receptacle in position for emptying its contents, and Fig. 3 is a fragmentary 50 longitudinal sectional view taken on line 3—3 of Fig. 2.

Like numerals of reference indicate the same parts throughout the three figures, in which—

55 1 indicates the can or receptacle and 2 indicates the cover which is provided with a

slight annular flange 3 to fit over the top edge 4 of the can or receptacle 1.

5 indicates a bail attached to the can or receptacle near the bottom 6 thereof for 60 conveniently manipulating the can or receptacle as when emptying the contents therefrom.

7 indicates the handle which is securely attached to the top or cover 2 at 8 and which 65 terminates in the two depending arms or members 9 which straddle the can or receptacle 1, and are pivoted at 10 to the slidable links 11 which operate in the guides 12 securely fastened to opposite sides of the can 70 or receptacle, each of which slidable links 11 are provided at their lower ends with an outwardly bent portion 13 which as is illustrated in Figs. 2 and 3 engage the guides 12 to limit the outward or upward movement 75 of the slidable links 11.

Referring particularly to the depending arms 9 it will be seen that the same are provided with an enlargement or cam-shaped portion 14 adjacent the slidable links 11 and 80 guides 12, which enlargement or cam-shaped portion 14 is designed to act upon the surface or edge of the guides 12 when the handle 7 and top 2 are swung into position shown in Fig. 2, thus maintaining the slid- 85 able links 11 in their properly extended position, and insuring a proper balance to the can or receptacle, while at the same time maintaining and positioning the cover 2 in proper location for quick and easy applica- 90 tion to the can or receptacle when the contents have been removed therefrom.

Having thus described the several parts of this invention, its operation is as follows: When grasping the handle 7 while 95 the can is in its normal vertical position the handle 7 and top 2 are raised into position shown in dotted lines in Fig. 1, thus providing ready transportation of the can. In order to empty the contents thereof the bail 133 100 is grasped and the can is turned into position shown in Fig. 2. This causes the cam-shaped portion 14 to engage the edge of the guide 12 thus effectually preventing the slidable link 11 from moving into the guide 105 12 and assuring its retention in its extended position, so that upon reapplication of the top 2 to the mouth of the can, proper clearance between the top 2 and the mouth of the can will be maintained.

Having thus fully described the invention it is apparent that the same is susceptible to

certain changes and alterations, and we consider ourselves clearly entitled to all such modifications as fall within the limit and scope of the appended claims.

5 What we claim as new and desire to secure by Letters Patent of the United States is—

- 10 1. A can or receptacle, including a top or cover, a handle thereon, a pair of arms depending therefrom and straddling the can, a pair of slidable links to which said depending arms are pivoted, a guide on the can for each slidable link, a stop on each slidable link for limiting the upward movement thereof and a cam-shaped portion on each of said depending arms for engagement with each of said slides to maintain the said slidable links in their extended positions upon movement of the said top into position
- 15 20 for uncovering the can.

2. A can or receptacle, including a top or

cover, a handle thereon, a pair of arms depending from said top or cover and straddling the can, slidable connections on the can to which said depending arms are pivoted and means on said depending arms for retaining said slidable connections in their extended positions when said top or cover is moved into position for uncovering the can.

3. A can or receptacle, including a top or cover, a handle thereon, a pair of arms depending from said top or cover to straddle the can and slidable connections on the can to which said depending arms are pivoted, substantially as described.

In testimony whereof, we affix our signatures, in presence of two witnesses.

CHARLES FAERBER.

JOHN HAMPTON SMITH.
